US0D1085758S

(12) **United States Design Patent** (10) **Patent No.:** **US D1,085,758 S**
(45) **Date of Patent:** **** Jul. 29, 2025**

(54) **SHELF**

(71) Applicant: **Adrian Steel Company**, Adrian, MI (US)

(72) Inventors: **Joshua Michael Gerez**, Tecumseh, MI (US); **Joshua Merle Rogers**, Adrian, MI (US); **Mark Anthony Henry, Jr.**, Adrian, MI (US); **Robert Michael Butcher**, Saint Charles, MI (US); **Peter Francis Rowlson**, Addison, MI (US)

(73) Assignee: **Adrian Steel Company**, Adrian, MI (US)

(**) Term: **15 Years**

(21) Appl. No.: **29/878,745**

(22) Filed: **Jun. 27, 2023**

(51) LOC (15) Cl. **12-16**

(52) U.S. Cl.

USPC **D12/425**

(57) **CLAIM**

The ornamental design for a shelf as shown and described.

DESCRIPTION

FIG. 1 is a front side perspective view of a shelf showing one embodiment of our new design;

FIG. 2 is a rear side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines in the drawings are included to show portions of the shelf that form no part of the claimed design.

1 Claim, 4 Drawing Sheets
